UNITED STATES PATENT OFFICE.

JOHN KEENAN, OF NEW YORK, N. Y.

LINOTYPE-MACHINE.

1,123,752.

Specification of Letters Patent. Patented Jan. 5, 1915.

Application filed June 11, 1912. Serial No. 702,999.

To all whom it may concern:

Be it known that I, JOHN KEENAN, a citizen of the United States, residing in the borough of Manhattan, in the city, county, and State of New York, have invented new and useful Improvements in Linotype-Machines, of which the following is a specification.

This invention relates to linotype machines or the like, and particularly to means to adapt the machine for casting successive linotypes or slugs from a series of set up matrices, the successive linotypes having consecutive numbers to utilize the same for "page numbering work."

Heretofore in producing linotypes from a series of assembled matrices, should it be desired to produce lines containing any variations of characters therein, it is necessary to distribute the matrices so set up and re-set the line to contain matrices of other character. In producing linotypes of page numbering work, in which successive page numbering of title is desired, it will be obvious that a great amount of time is wasted which might be saved by avoiding this distribution and resetting, and it is the object of the present invention to provide means whereby linotypes may be successively cast from a series of assembled matrices and an adjustable matrix or matrices having a plurality of characters, together with means to adjust said matrix or matrices in the line so assembled, whereby the successive linotypes may be consecutively numbered or lettered.

In the drawing accompanying and forming a part of this specification, Figure 1 is a sectional side elevation of so much of the mechanism of a Mergenthaler linotype machine as is necessary to an understanding of the invention. Fig. 2 is a perspective view, looking at the top, of the elevator slide for supporting the line of assembled matrices, illustrating an embodiment of my invention applied thereto. Fig. 3 is a perspective view of my improved matrix. Fig. 4 is a side elevation of a detail to illustrate the manner of adjusting the matrix and locking it in its adjusted position; and Fig. 5 is a plan view of the elevator slide guide illustrating the manner of releasably securing it in place.

Similar characters of reference designate like parts throughout the different views of the drawings.

In the drawings I have illustrated an em-

bodiment of my invention applied to the well known "Mergenthaler" linotype machine, and have shown such parts and so much of the machine as is essential to an understanding of the invention. It is to be understood, however, that the invention is not limited to use in this type of machine only, that it is not limited in its application, and that it may be embodied in other forms than herein shown, so long as means are provided whereby successive linotypes may be produced from a series of set up matrices and the successive linotypes provided with numbers in consecutive order. The essential construction of the different parts of the machine to which my invention is applied are not changed, except in the particulars to be hereinafter described to carry out my invention. In the present instance I have shown my invention applied to the elevator slide 6, slidably supported by the vise 7, having matrices carrying jaws 8, 8' to receive the matrices from the assembling position, said slide 6 being raised and lowered by a cam-actuated lever 9 pivotally connected thereto to carry the assembled matrices to the casting position, and from the latter to the transferring position wherein the line is transferred to the second elevator for distribution, all of which is common in said Mergenthaler machine.

In Fig. 1 the matrices are shown as having been carried by the elevator 6 to and supported in the vise 7, between said vise and the mold disk 10, and shown in dotted lines as carried by the elevator to the transferring position with the matrices in engagement with the elevator-slide guide 11, which guide is shown in full lines in normal position and in dotted lines thrown back when my matrices are used.

As already stated, in the ordinary operation of the machine the matrices are set up and assembled in the usual manner by a finger-manipulated key-board, and received by the jaws 8, 8' from the assembling position, carried to the casting position (shown in Fig. 1) when the linotype is cast, after which the matrices are carried to the transferring position, shown in dotted lines in Fig. 1, from whence they are transferred to the distributing mechanism. Should it be desired to produce another linotype identical with the previous linotype, wherein any change of a character or characters is

required, it is necessary to reset the line of matrices.

To permit the producing of successive linotypes from a single series of set up matrices I so mount the elevator-slide guide 11 that it may be adjusted to a position out of the path of the elevator slide with the assembled matrices when it reaches the transfer position as shown in dotted lines where-
10 by the matrices will not be transferred to the distributing mechanism. In the present instance the elevator slide guide 11 is pivot-
ally supported on the frame work, as at 12, whereby it is adapted to be swung up out of
15 the way of the ascending elevator slide, as shown in dotted lines in Fig. 1. In the present instance to lock the guide 11 in position for use in the ordinary operation of the machine, I provide locking bolts screw
20 threaded into the frame having wings 13 projecting laterally therefrom to engage over the guide, as clearly shown in Fig. 5, holding the cap or guide 11 firmly down in position on the framework (Fig.
25 1) to coöperate with the elevator 6 to transfer the matrices therefrom to the distributor mechanism.

To permit of the producing of successive linotypes having numeral characters the numerals of which consecutively advance in the successive linotypes, I provide a matrix or matrices 14 carrying a series of numeral dies 1 to 9 and 0, as shown in Fig. 3. These matrices are of greater length but of the same width as the ordinary matrices, but are not provided with the lugs whereby they are supported in the elevator jaws 8, 8'. Said matrices are provided at the edge opposite the character dies with serrations 40 or rack teeth 15, spaced to correspond with the height of the character dies. These matrices are carried by the jaws 8, 8' to be manually adjusted after each linotype has been produced and locked in their adjusted 45 positions by spring detents 16, engaging with toothed wheels 17 meshing with the matrix rack teeth and by means of said wheels 17 the matrices 14 are adjusted, the said detents and wheels being carried by a bracket 18 fixed to the top of the elevator slide 6. In producing successive linotypes having consecutive numbers the machine is started and the matrices for the subject-matter and number of the first page are set 50 up in the usual manner by the key board and the first linotype produced from said matrices. The guide 11 is then adjusted to its position out of path of the ascending elevator slide and assembled matrices. The 55 matrix or matrices at either or both ends set up and assembled by the machine are then removed and matrices as shown in Fig. 3 substituted therefor. Assuming the numeral characters are to appear on the left of the 60 linotype and the number of the pages are
65

to have from one to three digits, the three matrices set up and assembled at the right (Fig. 2) by the machine are removed and three of the matrices 14 are substituted therefor and so adjusted by the toothed wheel 17 that the character die "1" on the matrix at the extreme right will register with the mold 10 and a blank portion of the other two matrices registers with the mold when the linotype is cast with the numeral character "1". The matrix is then adjusted through its coöperating toothed wheel 17 one space after each linotype is produced until the linotype with the numeral character "9" has been produced when said matrix will be adjusted so that the character die "1" registers with the mold and the adjacent matrix is adjusted through its coöperating toothed wheel 17 so that the die for the digit "0" registers with the mold to produce the numeral character "10" on the succeeding linotype. The two matrices are then adjusted after each successive linotype is produced until the numeral character "99" is produced on a linotype when the third matrix is adjusted in a like manner. It will be understood that the machine will go through its regular operation after the production of a linotype; that is, the elevator slide with the matrices will proceed to the transferring position, but owing to the guide 11 being adjusted out of the path of said slide and matrices the matrices will again be carried by the elevator to the casting.

While I have shown the matrices 14 as being manually adjusted it will be understood that they may be mechanically or automatically adjusted after each successive linotype has been produced.

Variations may be resorted to within the scope of my invention.

Having thus described my invention, I claim:

1. In a linotype machine, the combination with the elevator arranged to receive a line of assembled matrices for presentation to the linotype producing mechanism, of matrix bars having a plurality of characters, and means to sustain and support said matrix bars in a predetermined position within the line, said means serving to adjust the matrix bars so that any desired character thereon will be in line with the characters composing the line.
2. In a linotype machine, the combination with the elevator arranged to receive a line of matrices for presentation to a mold to successively cast linotypes therefrom, of matrix bars containing a plurality of characters set within the line of matrices, and means carried by the elevator to adjust and sustain said matrix bars within the line to change the characters in successive linotypes.

3. In a linotype machine, the combination with the vertically movable elevator arranged to present a series of assembled matrices to the linotype producing mechanism, of a guide normally coöperating with said elevator to transfer the matrices therefrom, said guide adapted to be adjusted out of the path of the elevator to prevent the transferring of the matrices therefrom, whereby a single series of set up matrices will be successively presented to the casting position to successively produce linotypes therefrom, substantially as and for the purpose specified.
4. In a linotype machine, the combination with the vertically movable elevator arranged to present a series of assembled matrices to the linotype producing mechanism, of a series of matrix bars having a plurality of characters adjustably carried by said elevator within the line of matrices; a guide normally coöperating with said elevator to transfer the line of matrices therefrom; and means to adjust said guide out of the path of the elevator containing the line of matrices and matrix bars, substantially as and for the purpose specified.
5. In a linotype machine, the combination of matrices having a plurality of characters on one edge and a series of serrations or teeth on the opposite edge; a carrier to adjustably carry said matrices to present them to the linotype producing mechanism; and means to adjust said matrices in the carrier after each successive linotype has been produced, comprising toothed wheels to mesh with the teeth of the matrices; and detents to engage with said wheels and lock the matrices in adjusted position, substantially as and for the purpose specified.
6. In a linotype machine, the combination with the vertically movable elevator arranged to present a series of assembled matrices to the linotype producing mechanism, of a series of matrix bars having a plurality of characters adjustably carried by said elevator within the line of matrices; a guide normally coöperating with said elevator to transfer the line of matrices therefrom, said guide adapted to be swung up out of the way of the elevator; and means to lock said guide in position to coöperate with the elevator, substantially as and for the purpose specified.
7. In a linotype machine, the combination with the vertically movable elevator arranged to present a series of assembled matrices to the linotype producing mechanism, of a series of matrix bars having a plurality of characters adjustably carried by said elevator within the line of matrices; a guide normally coöperating with said elevator to transfer the line of matrices therefrom, said guide adapted to be swung up out of the way of the elevator; and means to lock said guide in position to coöperate with the elevator, comprising bolts screw threaded into the framework having laterally projecting wings to engage over the guide.
8. In a linotype machine, the combination of matrices having a plurality of characters and provided with rack teeth; a carrier for said matrices to present them to the linotype producing mechanism; and means carried by the carrier and engaging with the rack teeth of the matrices to adjust the same in the carrier and lock them in adjusted position.
9. In a linotype machine, the combination with a carrier for the assembled matrices to present them to the linotype producing mechanism, of matrices having a plurality of characters and provided with rack teeth, said matrices being carried by said carrier to have longitudinal adjustment therein; and toothed wheels mounted on the carrier coöperating with the rack teeth of the matrices to adjust the matrices in the carrier and lock them in adjusted positions, substantially as and for the purpose specified.
- JOHN KEENAN.
